United States Patent Office

Des. 177,281
Patented Mar. 27, 1956

177,281

LICENSE FRAME

Edwin L. Schwartz, Los Angeles, Calif.

Application August 16, 1955, Serial No. 37,502

Term of patent 14 years

(Cl. D14—6)

Fig. 1

Fig. 2

Fig. 3

Fig. 5

Fig. 4

Fig. 6

I claim:

The ornamental design for a license frame, substantially as shown.
